UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

PULLER-MACHINE.

1,145,619.

Specification of Letters Patent.

Patented July 6, 1915.

Application filed June 15, 1907. Serial No. 379,218.

To all whom it may concern:

Be it known that I, DUDLEY S. SEYMOUR, a citizen of the United States, residing at Oak Park, in the county of Cook, State of Illinois, have invented certain new and useful Improvements in Puller-Machines, of which the following is a description, reference being had to the accompanying drawing and to the letters and figures of reference marked thereon.

My invention relates to new and useful improvements in puller machines, preferably used in connection with sewing machines, although said puller may be used in connection with any other machine operating upon material wherein it is desired to assist the feed of such a machine by pulling the material operated upon through the machine.

20 The object of my invention is to provide a puller or auxiliary feed for a sewing machine or the like, which shall be durable and efficient in operation, and which shall also operate in unison with the feed of the sewing machine.

My invention consists in the parts, arrangements and improvements hereinafter shown and described and set forth in the claims.

30 In the drawings which show one embodiment of my invention,—Figure 1 is a front plan view of my improved puller, a portion of the work plate being broken away to expose the mechanism underneath the same; Fig. 2 is an end elevation of my improved puller shown attached to a sewing machine; Fig. 3 is a top plan view of a combined puller and sewing machine, certain parts being in section and certain parts broken away to expose the operating mechanism; Fig. 4 is a detail front elevation, partly in section, showing the operating eccentrics and their adjustment for operating the feed of the sewing machine and the feed of the puller; Fig. 5 is a detail, partly in section, showing the operating eccentrics and their connection to the puller shaft in side elevation; Fig. 6 is a detail, showing the support for the eccentrics in section, said section being taken on the line 6—6 of Fig. 3; Fig. 7 is a longitudinal sectional view through the puller shaft, showing the clutch for operating the same; and Fig. 8 is a sectional view on the line 8—8 of Fig. 7.

The sewing machine to which my improved puller is shown attached, is of the ordinary construction, and as shown in the drawings, is provided with two needles, 1, 1, which are carried by the needle bar 2 reciprocating in the head 3 supported on the overhanging arm 4. The presser bar 5 carries a presser foot 6 at the lower end, and the usual lever 7 for lifting the same is mounted on the head of the machine. I have also provided a lever 8 pivoted to the head of the machine, which extends underneath the stud 9 mounted on the presser bar 5, and said lever 8 is operatively connected by a suitable chain or other flexible connection 10, to a treadle or knee lever, whereby the same may be lifted. The work support 11 is spaced from the bed plate of the machine 12 in the usual manner. The feeding mechanism is the ordinary four-motion feed, and comprises a feed bar 13 carrying a feed dog 14. Said feed bar is pivoted to the rocking frame 15, at its rear end, through which said feed bar is given its longitudinal or feeding movements. The feed bar is given its rise and fall from the usual eccentric mounted on the main shaft. The rocking frame 15 has an arm 16 rigidly secured thereto, and said arm is pivotally connected to an eccentric strap 17 by a ball stud connection 18, as clearly shown in Figs. 3, 5 and 6. Said eccentric strap 17 surrounds an eccentric 19 adjustably secured to a supporting plate 20. Said eccentric 19 is provided with a dove tail portion 21, which engages a coöperating dove tail projection carried by the support 20. The support 20 is rigidly secured to the main shaft 21^a, by a set screw 22, as shown in Fig. 6. This support 20 is provided with outwardly extending ears 23, 23, through which is passed a bolt 24 having an enlarged portion 25 secured thereto between the ears 23, 23, whereby the bolt 24 is held in said ears, so that the same may be rotated, but said bolt is prevented from longitudinal movement through said ears. The enlarged portion 25 preferably has its sides slabbed, whereby the same may be engaged by a wrench. The bolt 24 is provided with right and left hand threads at its opposite ends. The eccentric 19 is provided with a perforated lug 26, which is threaded for engagement with the bolt 24 (see Fig. 4). The

eccentric 19 is slotted as at 27, (see Fig. 5), so that said eccentric may be moved transversely across the main shaft, and thereby the throw of the eccentric strap altered. It 5 will be obvious that when the threaded bolt 24 is turned in one direction, the eccentric will be moved toward the center of the shaft by means of the threaded engagement between the bolt and the lug 26, carried by the 10 eccentric and when the bolt is turned in the opposite direction the eccentric will be moved away from the center of the main shaft.

My improved puller consists of a bed 15 plate plate 28, from which rises an overhanging arm 29, carrying at the forward end thereof a head 30, in which reciprocates a rod 31, carrying at the lower end thereof one member of the feeding mechanism of my 20 improved puller. The bed plate 28 of the puller is provided with suitable supporting brackets 32, 32 (see Figs. 1 and 3). On said brackets is the cloth plate or work support 33. The supporting brackets 32 are of 25 such height that when said puller is mounted on a common base 34 (see Fig. 2) with a sewing machine, the cloth plate 33 of the puller is in the same plane with the cloth plate 11 of the sewing machine, so that material operated upon by the sewing machine 30 may be passed directly from one cloth plate onto the other.

Passing through the brackets 32 is a shaft 35 which carries at its forward end a feed 35 wheel 36, which coöperates with a feed wheel 37 rotatably mounted in the yoke 38 secured to the lower end of the bar 31, as shown in Fig. 1 of the drawing. The feed rollers 36 and 37 as clearly shown in Figs. 40 1 and 2, are provided with projecting ribs or teeth 39 and 40, respectively, which are so shaped and spaced that one intermeshes with the other. I have also provided my feed rollers with circumferential grooves 41, 42, 45 which are spaced the same distance apart as the needles of the sewing machine, so that stitches formed by the stitch-forming mechanism of the sewing machine will pass through said grooves and all liability of crushing or destroying the stitch in any 50 way, is avoided. The grooves, however, are of sufficient depth so that when no material is passing between the rollers but the machines are chaining from one stitched article 55 to another, the chain of stitches will be engaged by the feeding rolls and fed along, although said chain of stitches should lie in the grooves.

In order to intermittently rotate the feed 60 wheel 36, I have provided the shaft 35 with a suitable clutch mechanism, which is operated from an eccentric carried by the main shaft of the sewing machine. Said clutch mechanism consists of a collar 43 (see Fig. 65 7), secured to the main shaft 35 by means of

a set screw 44. Said collar is provided with an enlarged bore 45 in one end thereof, into which fits a sleeve 46, loosely mounted on the shaft 35. Said collar is also provided with cam-shaped recesses 47 (see Figs. 5 and 70 7), in which are located small rollers 48, 48. A spring 49 is seated in said recess, and normally forces the roller up the cam surface of the recess into gripping contact with the sleeve 46. Said sleeve 46 has rigidly 75 secured thereto an arm 50. When said arm 50 is vibrated in the direction of the arrow shown in Fig. 5, the sleeve 46 through the rollers 48 grips the cam face of the recesses in the collar 43, and turns said collar, thereby imparting a movement to the main shaft 35. When, however, the sleeve 50 is vibrated in the opposite direction, the rollers 48 are moved out of gripping contact with the collar 43 and the sleeve is moved relative 80 to the main shaft.

In order to provide a means for holding the main shaft from backward movement when the arm 50 is vibrated in the direction opposite from that shown by the arrow in 90 Fig. 5, I have provided a bracket 51, which is secured to the bed plate of the puller 28 by suitable screws, and at its upper end is secured to a collar 52, which is loosely mounted on the main shaft, and which is 95 also provided with an enlarged bore or recess 53, (see Fig. 7), which receives a reduced portion of the sleeve 43. Said collar 52 is provided with recesses 54, 54, having cam faces similar to the recesses formed in 100 the collar 43, but oppositely disposed relative thereto. Said recesses 54 are each provided with a roller 55 and with a spring seated in said recess 54, and engaging said roller, whereby the same is normally held in 105 gripping contact with the sleeve 43.

The manner of operating my clutch will be obvious from the above description. As the arm 50 is vibrated in the direction of the arrow in Fig. 5, the sleeve 46 will grip the collar 43 through the gripping rollers 48, and turn the main shaft to the extent to which the arm 50 is vibrated when the arm 50 is moved in the opposite direction. The gripping rollers 55 will clutch the sleeve 43, and prevent the main shaft from rotating in a backward direction. By this form of vibrating clutch and locking clutch, I have provided a clutch mechanism, whereby small increments of movement may be given to the intermittently rotated shaft, and said shaft be firmly held in the precise position to which it is turned. By this form of structure, I have also provided a clutch mechanism which is practically noiseless in 115 its operation.

The arm 50 is connected by a suitable link 56 to an eccentric 57, mounted on the main shaft 21 of the sewing machine. Said eccentric 57 is provided with a portion having 120

a dove tail recess 58, which engages a co-operating dove tailed projection 59, mounted on the support 20, above referred to. (See Fig. 3). The eccentric 57 is also provided with a threaded lug 60, which engages the threaded bolt 24. It will be obvious that when said bolt 24 is turned, that the eccentric 57 is moved toward or from the axis of the main shaft, and thereby the throw of the eccentric and the feed movement given to the main shaft of the puller, is varied. As above noted, the bolt 24 is provided with right and left hand threads and the eccentrics 57 and 19 are disposed upon opposite sides of the center of the main shaft, as clearly shown in Fig. 5. By turning the bolt 24, therefore, the eccentrics will be simultaneously moved toward or from the center of the main shaft and the throw of said eccentrics will, therefore, be simultaneously adjusted. If the eccentrics are timed so that the throw of each eccentric causes an equal movement of the sewing machine feed and the feed of the puller, for any given length of feed, when said length of feed is adjusted by moving one eccentric away from the center of the main shaft or toward the same, the other eccentric will be similarly moved, and a similar adjustment would be made in the movements of the puller feed. By this arrangement of parts the two feeds may be set to move in unison and whenever the feed of the sewing machine is altered to lengthen the stitch, the feed of the puller will be correspondingly altered, and the feeds will still move in unison. Suitable check nuts 60^a and 60^b are provided, to hold the eccentrics in their adjusted position.

The feed roller 37 is held in engagement with the material by a flat spring 61, mounted in the overhanging arm of the puller, and having one end thereof resting on a lug 62 while the other end thereof engages the collar 63 on the rod 31. The screw 64 engages the spring between its ends and by adjusting said screw the tension of the spring may be increased or decreased, and the pressure of the feed roller 37 on the material correspondingly varied.

As a means for lifting the feed roller 37 from the material, I have provided a lever 65, pivoted at 66 to the overhanging arm 29. The forward end of said lever engages a stud 67 secured to the rod 31, while the other end of said lever is provided with an eye 68, which is engaged by a suitable chain or other flexible connection 69. As shown in Fig. 2, the flexible connection or chain 69 and the chain 10, are joined together and connected by a single chain to a knee lever or foot treadle, so that the presser bar of the sewing machine and the feed 37 of the puller may be simultaneously lifted from the material whenever desired. The lever

65 is held by means of a spring 70, normally in contact with the lug 71 on the head of the machine.

The operation of my device will be obvious from the above description. The puller is attached to a sewing machine or any other machine in which it is desired to assist the feed thereof. The material after passing through the machine, is passed to the puller between the feed rollers thereof, and as the feed of the main machine operates the feed of the puller will be operated in unison, and the material pulled through the machine. If desired, the stroke of the puller feed may be so adjusted as to be slightly in excess of that of the feed of the main machine and thereby the material put under slight strain.

It will be obvious that instead of operating the puller from an eccentric on the main shaft said puller may be operated from the rocking frame of the feed dog or from any other suitable mechanism, whereby the same may be moved in unison with the feed dog of the machine. If said puller were operated from the rocking frame of the feed dog, then all adjustments of the feed dog whereby the stroke of the feed is varied, would produce a like variation in the feeding of the puller, so that the feed of the puller and the feed of the main machine will be kept in unison for various lengths of feed movements.

It will be obvious that from certain aspects, my invention is not limited to rotary feeding wheels, but that any other form of intermittent feed may be substituted therefor, the essential feature being that the feed of the puller shall operate in unison with the feed of the sewing machine for all variations in the length of stitch.

When it is desired to adjust the throw of the puller independently of the feeding mechanism of the sewing machine, the nut 50^a (see Fig. 4), may be loosened and the connection between the link 56 and the lever 50 moved toward or from the center of the shaft 35. The arm 50 is slotted at 50^a to allow of this adjustment.

Having thus described my invention, what I claim as new and desire to secure by Letters Patent, is:

1. The combination with a sewing machine, having a feeding mechanism, of an independently mounted puller comprising a feeding device, means for operating said feeding mechanism and said feeding device in unison, and a common support on which said sewing machine and puller are mounted.

2. The combination with a sewing machine having a feed dog, and means for operating the same, including an eccentric, of a puller comprising feeding devices and means for operating the same, including an

eccentric and means for simultaneously adjusting the two eccentrics to vary the throw of the feed dog and feeding device of the puller.

5. 3. The combination with a sewing machine having a main shaft, a feed dog, means for operating the same including an eccentric carried by said main shaft, of a puller comprising feeding devices and means for 10 operating the same, including an eccentric mounted on said main shaft, and a common support secured to said main shaft on which said eccentrics are carried.

15. 4. The combination with a sewing machine having a main shaft, a feed dog, means for operating the same including an eccentric carried by said main shaft, of a puller comprising feeding devices and means for operating the same, including an eccentric 20 mounted on said main shaft, and a common support secured to said main shaft on which said eccentrics are carried, and means for simultaneously adjusting said eccentrics on said support.

25. 5. The combination of a sewing machine having an overhanging arm, a work support and a feeding mechanism, of a puller comprising an overhanging arm parallel to the overhanging arm of the sewing machine, a 30 work support arranged in the same plane as the work support of the sewing machine and a feeding device, means for operating the feeding mechanism of the sewing machine and the feeding device of the puller in unison, and shiftable devices for equally 35 adjusting the means for operating the feeding mechanism of the sewing machine and the means for operating the feeding device of the puller.

40. 6. The combination with a sewing machine, including a feeding mechanism, a work support, and an overhanging arm, of a puller comprising a work support, an overhanging arm, a feed wheel mounted beneath the work support, a presser wheel carried by the overhanging arm of the puller, means for intermittently rotating said feed wheel in unison with the feeding movements of the feeding mechanism, and a common 45 supporting base for the sewing machine and the puller.

7. The combination with a sewing machine, having a work support and an overhanging arm, of a puller having a work 50 support and an overhanging arm, and a common support, whereby said puller is connected to said sewing machine with the overhanging arms parallel and the work supports in the same horizontal planes.

8. A puller comprising in combination, a 60 work support, an overhanging arm, a feed wheel mounted beneath said work support, a presser wheel carried by said overhanging arm, a vibrated arm having a clutch for rotating said feed wheel in one direction, and a stationary bracket having a clutch for preventing backward rotation of said feed wheel.

9. The combination of a sewing machine, having a needle, of a puller located in the 70 rear of the sewing machine and having a feed wheel and a presser wheel, said wheels having intermeshing fabric-engaging teeth or projections, and a circumferential groove formed therein to receive the line of 75 stitches.

10. The combination of a sewing machine including a main shaft, a feed dog, an actuating device carried by the main shaft, means operated thereby for moving said feed dog back and forth, a puller in rear of the feed dog and comprising a feed wheel, a second actuating device carried by said main shaft and means operated thereby for intermittently rotating said feed wheel of 85 the puller in unison with the feeding movements of the feed dog and means for shifting said actuating devices on the main shaft for simultaneously varying in unison the length of the stroke of said feed dog and 90 said feed wheel.

11. The combination with a sewing machine having a feed dog, and means for operating same including an eccentric, of a puller comprising a feeding device and 95 means for operating same, including an eccentric oppositely disposed to first said eccentric, and means for simultaneously adjusting the two eccentrics to vary the throw of the feed dog, and the feeding device of 100 the puller.

12. In a sewing machine including an overhanging arm, a presser bar mounted thereon, a lever secured to the rear side of the overhanging arm for lifting said bar, 105 of a puller comprising an overhanging arm, a presser bar mounted thereon, a lever secured to the front side of the second overhanging arm for lifting said presser bar, and means for simultaneously operating 110 said levers.

In testimony whereof I affix my signature, in presence of two witnesses.

DUDLEY S. SEYMOUR.
